To all whom it may concern:

Be it known that I, Yvonne Gourfain, a citizen of the United States of America, residing in the city of New York, county of New York, and State of New York, have invented a new, original, and ornamental Design for a Dress Ensemble, of which the following is a specification, reference being had to the accompanying drawing, forming part thereof.

The characteristic feature of my design resides in the combination on the ensemble disclosed of the jacket member which is trimmed as shown.

I claim:
